The ornamental design for a stock car racing souvenir wreath, as shown and described.

DESCRIPTION

FIG. 1 is a front elevational view of the stock car racing souvenir wreath showing my new design;

FIG. 2 is a rear elevational view thereof;

FIG. 3 is a left view thereof;

FIG. 4 is a right view thereof;

FIG. 5 is a top plan view thereof; and,

FIG. 6 is a bottom plan view thereof.

In FIG. 1, the broken line showing of the word "logo" is for illustrative purposes only and forms no part of the claimed design.
